GEORGE PATTEN, OF CHESTER, PENNSYLVANIA.

Letters Patent No. 72,533, dated December 24, 1867; antedated December 7, 1867.

IMPROVED MACHINE FOR REMOVING MOULDED FORMS FROM THE PRESS.

The Schedule referred to in these Letters Patent and making part of the same.

TO ALL WHOM IT MAY CONCERN:

Be it known that I, GEORGE PATTEN, of Chester, in the county of Delaware, and State of Pennsylvania, have invented a new and useful Improvement in Machinery for Removing Moulded Forms from the Press; and I do hereby declare that the following is a full, clear, and exact description of the construction and operation of the same, reference being had to the annexed drawing, and the letters of reference marked thereon, forming part of this specification. In the drawing—

Figure 1 is a side elevation of the machine, with receiving-carriage.

Figure 2 is a plan of the same.

Figure 3 is an end elevation, showing in dotted lines the discharge-position of the conveyor.

Figure 4 is a vertical section through the axis of solid shaft S' and middle of conveyor, showing palms in discharge-position.

Figure 5 is a cross-section of shaft on x x.

Figure 6 is a cross-section of shaft on y y.

Figure 7 is a cross-section of shaft on z z.

Figure 8 is a cross-section of arm E, showing pendent stud for operating spring-detent q.

Figure 9 is a vertical section on t' t', fig. 2, showing rocking-lever R' and slide f operating same.

Similar letters of reference in the several figures denote the same part.

The mechanism which constitutes the subject-matter of this invention is designed as an adjunct to a machine by which an artificial building-stone is moulded from a composition of sand and lime, or any other suitable material admitting of cohesion, the form or block being shaped in a mould-box, which, after having performed its function, slides down and leaves the finished form or block resting upon the bed of the press ready for removal. The nature of the composition is such that the form cannot be pushed from the bed, as in brick-moulding machines, without breaking, but requires to be carefully lifted therefrom by hand previous to being conveyed to a drying-rack by an off-bearer. The automatic removal of these forms from the bed of the press is the object of this invention.

The nature of the invention consists in grasping the moulded form, as it rests upon the bed of the press, between two adjustable palms attached to a conveyor, the form thus grasped being carried to and deposited upon a suitable receiver, the grasping and releasing of the form and feeding of the receiver being performed automatically by the mechanism which operates the conveyor.

In the drawing, W represents the bed of the press, from which the moulded form is to be carried off. C is a crane-arm, secured to a vertical hollow shaft, S, stepped at a, and held by guide-block b. This shaft is movable ninety degrees by the arm c of the enclosed solid shaft s', engaging the edge of the opening in the hollow shaft, through which the said arm passes, the power to move the entire mechanism being applied to this arm c. The extremity of the arm C widens and forms the carrying-head H, in slots d d, fig. 4, of which move slides e e, which, by means of the hangers f f, carry the horizontal bars B B. Connected with these bars, by the screw-bolts i, are the palms P P, between which and the bars B are inserted the cylinders g g, of rubber or other suitable elastic substance. The bolts are permanently fastened to the palms, so that, by the nuts h h, the palms are made to approach or recede from the bars B, thus affording a delicate adjustment of the space between the palms. The upper surfaces of slides e have pins, n, engaging slots, m, in the opposite ends of a vibrating plate, D, which moves upon a central bolt, l, passing through the head H, the effect of this vibration being to move the slides e e back and forth in the slots d, and thus move the palms P. The plate D is acted upon by springs w, to give motion in the direction which moves the slides e outward; and power applied to the stud o, upon the top of the plate, carries it in the direction which closes the slides. When the slides e e are carried inward, and the palms P closed, the plate D is held in position by the spring-detent q. Secured to the solid shaft s', and passing through an opening in the hollow shaft S, is the arm E, on one side of which is the pendent stud r, shown fully in fig. 8. Upon the hollow shaft S, below the arm C, is the arm A, whose collar, u, turns freely upon the hollow shaft, and is supported by the projection v on the shaft. This arm A carries a plate, F, shaped as shown in fig. 2, and operated as will be hereinafter set forth. Below the arm A, and movable upon the hollow shaft S, is the feed-arm G. This arm extends over the ratchet R on the carriage-frame I, the pawl p, on its extremity, engaging said ratchet. Upon the upper surface of the collar of this arm is a spring-catch, x, fig. 7, whose point presses against the shaft, and, at the proper time, engages the notch e'' therein. The backward motion of the arm is limited by the standard L, the shaft S slipping within the collar y during the

remainder of its movement. The spring t , upon the standard M , gives this arm G a tendency towards the standard L , thus causing the shaft S to carry it until it comes in contact with the said standard. The standard M , also, carries a spring, z , which acts upon the arm A , giving it a tendency towards the table of the receiver.

The operation of the machine is as follows: Starting with the conveyor over the bed W of the press, the palms embracing but not touching the moulded form, power is applied to the arm c of the shaft s' , turning said shaft within the hollow shaft S sufficiently far for the arm E , by pressing on stud o , to turn the plate D about its centre bolt l , until its lip, d' , is caught by the spring-detent q . This causes the form to be grasped by the palms $P P$. The arm c , at this instant, reaches the extent of the opening in the hollow shaft S , and, pressing against its edge, turns the hollow shaft, carrying the moulded form from off the bed of the press and upon the plate F . When the entire form is upon the plate F , the foot of the stud a' , pendent from the head H , forces back the detent b' , and releases the plate F from its connection with the press. At the same time this foot engages the protruding lip m' of the rocking-lever catch R' , shown in detail in fig. 9, and causes the plate F to move with the conveyor towards the receiving-table T . When the edge e' of the plate F is nearly in contact with the table T , the projecting end of the slide f' encounters the edge thereof. The slide f' is forced back, carrying the lip m' of the rocking-lever catch R' below the surface of the plate F , and elevating the lip n' above the surface. This permits the palms and the grasped form to pass from the plate F to the table T , and when the palms are parallel with the edge of the table the motion ceases. The shaft S turns within the collar y of arm G , until the point of the catch x engages the notch e'' in said shaft. Then the arm G moves with the shaft S , and the receiving-carriage is moved the requisite distance for the reception of the moulded form. This motion terminates at the same instant that the conveyor stops. The foot of the hollow shaft and its step are so constructed that at the commencement of the motion of the conveyor, after the form is grasped, the shaft and all that it carries are lifted about the sixteenth of an inch, thus causing the form to clear the bed of the press at the commencement of its motion, and also to pass clear of the table T after leaving the plate F . At the termination of the movement, the shaft settles to its original position, and the form rests upon the table, still grasped by the palms. The reverse movement of the solid shaft s' now begins. During the passage of the arm c , within the opening through the hollow shaft S , the arm E is moved in the reverse direction from that which closed the palms, causing the stud r to press on the tail of the detent q and release the vibrating-plate D . This plate, moving under the action of the springs w , moves the slides e outward, opens the palms $P P$ to the position shown in dotted lines, fig. 3, and releases the moulded form. The arm c now meets the edge of the opening through the hollow shaft, giving it motion and carrying it to the position from which it started. The spring z , acting against the arm A , retains the plate F against the table T , until the foot of the stud a' encounters the projecting lip n' of the rocking-lever R' , and carries the plate with the palms. When the plate nears the face of the press, the protruding end of the slide f' (the opposite from that which projected during the forward movement) is forced back by this face, carrying downward the lip n' , and permitting the palms to pass from the plate to the bed of the press. At the instant of release of the stud a' by lip n' , the spring-detent b' engages the face of the bed W , and holds the plate F until it is released by the return of the conveyor, as before set forth. At the beginning of the return-movement of the conveyor, the arm G , under pressure of the spring t , moves with the shaft S , carrying the pawl p backward over the ratchet R , until the standard L is encountered; the arm then stops, and the shaft S turns within the collar y , the detent x slipping from the notch e'' as the shaft turns from it.

All parts being now in the position from which they started, the several operations just described are repeated, and another form delivered, the movement of the arm c , which produces the entire action, being governed by the machinery operating the press in which the moulding is performed.

Although the functions of the mechanism here considered end with the deposit of the form upon the table of the receiver, it will not be out of place to state that the top of this table is designed to be removable from the frame, so that when the receiver is rolled to the end of the drying-rack with its load of moulded forms, this top will be automatically lifted from the frame and deposited upon the drying-rack. The mechanism by which this is accomplished, and the top with its load stowed away in its proper place upon the rack, will form the subject of a distinct patent, and need not be more particularly mentioned in this connection; this mention being made merely to show that the invention above described is the first part of a claim of mechanism by which the moulded forms are automatically taken from the press and deposited in their places on the drying-racks.

Having described my invention, and the operation of the same, what I claim as new, and desire to secure by Letters Patent, is—

1. The adjustable palms $P P$, in combination with the slides e and vibrating-lever plate D , or their equivalents, automatically operated to grasp a moulded form with the pressure requisite for removal, substantially as set forth.
  2. Automatically grasping and releasing moulded forms by the action of the conveying-mechanism, substantially as set forth.
  3. The combination of the feed-arm with the conveyor and receiver, substantially as set forth.
  4. The plate F , or its equivalent, constructed and operating substantially as set forth.
- In testimony whereof, I have hereunto set my hand, this first day of May, 1867.
